MEANS FOR ELIMINATING FADING

Application filed June 19, 1929, Serial No. 372,152, and in Germany June 30, 1928.

It is known that fading actions manifest themselves often only for a definite wave-length, but not in a slightly different wave.

The present invention is predicated upon the practical use of this particular property of the fading phenomena, with the end in view of obviating the disturbances caused by fading actions.

For this purpose, transmission according to this invention is effected on two or more carrier waves which differ comparatively but little from each other, so that, if one of the waves happens to experience fading trouble, the other wave or waves will be transmitted.

Two embodiments based upon the fundamental idea of the invention are shown in the drawing.

In the circuit arrangement shown in Figure 1, the two tubes I and II constitute the first stage of a usual amplifier cascade, and their tuning is so chosen that the difference in their wave-length is but little compared with the waves themselves. This can be insured most suitably by the convenient selection of the grid crystals k_1 and k_2 , respectively.

For instance, if the mean frequency is 2.5×10^6 cycles per second, then the difference of about 1250 cycles per second will suffice in the majority of cases. If, then, the frequency is raised, say, eight times by the following stages as usual, there results a difference between the waves sent out of about 10000 cycles per second. In the following stages, circuits tuned to two waves are not required, indeed, it is sufficient to tune them to the mean wave. Thus A_1 , an amplifier, is tuned to the mean wave-length, M indicates any suitable modulating source connected to the apparatus in any well known manner and A_2 , may be an amplifier and frequency multiplier.

It is advisable to set the wave-lengths, for

instance, by variable capacities of suitable kind, C_1 and C_2 , connected in the grid circuit of tubes 1 and 2.

The scheme illustrated in Figure 2 is fundamentally identical with Figure 1, except that the two tubes are here connected in phase-opposition (push-pull-fashion).

The condensers C_n as their labels indicate, are neutralizing condensers and prevent the reaction of one oscillator upon the other and vice versa.

I claim:

1. In a system for the reduction of fading, an electron discharge device oscillator, a crystal for maintaining the frequency of oscillation of the electron discharge device oscillator at a predetermined frequency, another electron discharge device oscillator, a crystal for maintaining the frequency of said last mentioned oscillator at a value slightly different from the frequency of said first mentioned oscillator, means for coupling the output circuits of the oscillators together, means for amplifying the combined output of the oscillators, means for modulating the amplified energy, and means for transmitting the resulting modulated oscillations.

2. In apparatus of the character described, an electron discharge device oscillator, a crystal for maintaining the frequency of oscillation of the electron discharge device oscillator at a predetermined frequency, another electron discharge device oscillator, a crystal for maintaining the frequency of said last mentioned oscillator at a value slightly different from the frequency of said first mentioned oscillator, means for coupling the output circuits of the oscillators together, neutralizing condensers connected to the output and input circuits of said oscillators for preventing reaction of one oscillator upon the other, and means for utilizing the combined outputs of said oscillators.

MENDEL OSNOS.
